UNITED STATES PATENT OFFICE.

FREDERICK H. L. JAMES, OF PAWTUCKET, RHODE ISLAND, ASSIGNOR TO SACO AND PETTEE MACHINE SHOPS, OF NEWTON, MASSACHUSETTS, A CORPORATION OF MASSACHUSETTS.

CLEANSING-TRUNK FOR COTTON OR OTHER PICKERS.

SPECIFICATION forming part of Letters Patent No. 690,654, dated January 7, 1902.

Application filed August 30, 1901. Serial No. 73,809. (No model.)

To all whom it may concern:

Be it known that I, FREDERICK H. L. JAMES, a citizen of the United States, residing at Pawtucket, in the county of Providence and State 5 of Rhode Island, have invented a new and useful Improvement in Cleansing-Trunks for Cotton or other Pickers, (Case D) of which the following is a full, clear, and exact description, reference being had to the accompanying drawings, forming a part of this 10 specification, in explaining its nature.

The invention is represented as applied to an inclined cleansing-trunk; and it relates to means for receiving, releasing, and feeding 15 dirt from the passing cotton or other fiber.

I will now describe the invention in connection with the drawings, wherein—

Figure 1 is a view in end elevation of an inclined cleansing-trunk having the features 20 of my invention. Fig. 2 is a view of a portion of the same, enlarged, also showing a part of the interior construction; and Fig. 3 is a view in cross-section, enlarged.

In the drawings, A represents the passage 25 in the trunk through which the cotton or fiber is drawn or impelled.

B represents the bottom of the passage and which is provided with narrow dirt-escape openings b by the narrow bars b', which extend 30 across the trunk from side to side thereof and are supported at their ends.

C represents dirt-receiving chambers extending crosswise the trunk and of any desired or suitable width, each of which receives 35 dirt through the openings b of the bottom B from the passing cotton or fiber and retains it until released. Each chamber is formed by the stationary cross-partitions c and the movable partitions or gates c'. Each movable 40 partition is in extension of the fixed partition c and is attached at its upper end to a cross-shaft c², having bearings upon each side of the trunk. The ends of these shafts extend from one side of the trunk sufficiently to receive 45 arms connecting them with an operating-bar D. Each of said arms is lettered d. Each is fast to the outer end of the cross-shaft and is pivoted at d' to the bar D. The movement of this bar D in one direction will cause

all the movable partitions or gates c' to be 50 moved in that direction. Ordinarily the movable sections of the partitions occupy a position to close the chambers C. When it is desired to free the chambers from dirt, the partitions or gates are then moved downward, 55 thereby freeing themselves and the chambers from dirt resting against or in them and also providing an unobstructed escape-passage for the dirt upon the bottom E, the dirt sliding down the bottom by gravity. 60

To conveniently move the bar D, I have represented it as connected with a lever F through one of the arms d, the arm f, and the link f'. The arm f is mounted upon the shaft c², and the link f' is pivoted at f² to the lever 65 F and to the end of the arm f. The lever F is pivoted at f³, and the clamping-nut f⁴, mounted on the threaded end of the pivot and provided with a handle f⁵, is adapted to be turned against the lever to lock it in the position which it has when the partitions or gates are wide open or when closed or in any intermediate position. In Fig. 2 the partitions or gates are represented as closed, and the lever and its connections with the gates 70 are shown in the positions which they then occupy. An upward movement of the lever causes the arm f to transmit the motion through the arm d to the bar D, moving it lengthwise the trunk and in a direction to 75 turn all the shafts c² of the various movable partitions or gates c' to the position represented by dotted lines in Fig. 2, thereby converting a portion of each chamber into a continuous escape-passage having an inclined 80 bottom and through which the dirt in the chambers slides or falls. An exhaust may be used for assisting in the removal of the dirt through this passage when open, if desired. 85

Having thus fully described my invention, I claim and desire to secure by Letters Patent of the United States—

1. In a cleansing-trunk for cotton or other pickers, a passage through which cotton or other fiber is fed, a grated bottom to said passage through which dirt may escape from the passing cotton or fiber in said passage, and

dirt-receiving chambers beneath said bottom having gates or partitions separating the same, and so movable that a portion of the chambers may be converted into a dirt-escape 5 passage.

2. In a cleansing-trunk for cotton or other pickers, a passage through which cotton or other fiber is fed, a grated bottom thereto, dirt-receiving chambers beneath said passage 10 connected therewith by openings through which dirt may pass from the said passage and which chambers are separated by movable gates or partitions, which serve in one capacity to separate the chambers and in another capacity to open them so that they then 15 form a continuous escape-passage.

3. In a cleansing-trunk for cotton or other pickers, a passage through which cotton or other fiber is fed, a grated bottom thereto, a 20 line of dirt-receiving chambers beneath said passage connected with it by openings and the bottoms of which chambers form a continuous incline, and movable gates or partitions between the chambers for closing and 25 opening the same.

4. In a cleansing-trunk for cotton or other pickers, a passage through which cotton or other fiber is fed, a grated bottom thereto, and the dirt-receiving chambers C beneath said

30 passage having the inclined bottom E and the partitions C' extending to the bottom E and movable downwardly from an inclined closed position to open the chambers and provide a dirt-escape.

35 5. In a cleansing-trunk for cotton or other pickers, a passage through which cotton or other fiber is fed, a grated bottom thereto, the dirt-receiving chambers C beneath said passage, and the movable partitions between 40 them connected with each other to be simultaneously moved in the same direction, either to open any number of chambers to form an escape-passage or to close them.

45 6. In a cleansing-trunk for cotton or other pickers, a passage through which cotton or other fiber is fed, a grated bottom thereto, the dirt-receiving chambers, their movable partitions, a common operating-lever and means for connecting said lever with the various 50 movable partitions.

55 7. In a cleansing-trunk for cotton or other pickers, having a passage through which cotton or other fiber is fed and a grated bottom thereto, the combination of a dirt-escape passage adapted to be converted into a series of dirt-receiving chambers, movable gates or partitions for transforming the one into the other, means for connecting the gates or partitions together whereby they may be simultaneously moved, and means for locking them 60 in their open position.

8. In a cleansing-trunk for cotton or other pickers, having a passage through which cotton or other fiber is fed and a grated bottom 65 thereto, the combination of a dirt-escape pas-

sage adapted to be converted into a series of dirt-receiving chambers, movable partitions or gates for transforming the one into the other, means for connecting the gates or partitions together whereby they may be simultaneously moved, and means for locking them 70 in their closed position.

9. In a cleansing-trunk for cotton or other pickers, having a passage through which cotton or other fiber is fed and a grated bottom 75 thereto, the combination of a dirt-escape passage adapted to be converted into a series of dirt-receiving chambers, movable partitions or gates for transforming the one into the other, means for connecting the gates or partitions together whereby they may be simultaneously moved, and means for locking them 80 in their open and in their closed positions.

10. In a cleansing-trunk for cotton or other pickers, the combination of a passage through 85 which cotton or other fiber is fed, and a grated bottom thereto with a dirt-escape passage adapted to be converted into a series of dirt-receiving chambers, movable partitions or gates for transforming the one into the other, 90 means for connecting the gates or partitions together whereby they may be simultaneously moved, and means for locking them in any desired position.

11. The combination in a cleansing-trunk 95 for cotton or other pickers of the passage through which cotton or other fiber is fed, a grated bottom thereto, with a plurality of dirt-receiving chambers beneath said grated bottom, and a gate or movable partition adapted 100 in one position to close a chamber from the next in order, and in another position to connect the same.

12. The combination in a cleansing-trunk 105 for cotton or other pickers of a passage through which cotton or other fiber is fed, a grated bottom thereto, with a plurality of dirt-receiving chambers, a partition between the same, and means for moving it from without the trunk to connect the chambers. 110

13. The combination in a cleansing-trunk for cotton or other pickers of the inclined passage through which cotton or other fiber is fed, its inclined grated bottom, the dirt-receiving chambers C having an inclined bottom, the fixed cross-partition and the hinged movable partition in extension of the fixed partition between it and the inclined bottom. 115

14. The combination in a cleansing-trunk for cotton or other pickers of a passage 120 through which cotton or other fiber is fed, a grated bottom thereto, with a plurality of dirt-receiving chambers, a movable partition between them, and means for moving said partition and for locking it in any desired 125 position.

FREDERICK H. L. JAMES.
